CAR CONSTRUCTION

William J. Hosceit, Chicago, Ill., assignor to
 Rodger Ballast Car Company, Chicago, Ill., a
 corporation of Maine

Application September 30, 1933, Serial No. 691,606

15 Claims. (Cl. 105—255)

This invention relates to new and improved closure means and a latching device therefor, characterized as especially adapted for use on hoppers and particularly, as here illustrated, on hoppers of railway cars.

It is an object of this invention to provide a door or closure, a frame therefor, cooperating latching mechanism on the door and frame respectively, and a hinge device for the door or closure of such character that the closure can be brought to closed position and thereafter caused to move bodily with respect to the frame to effect a tight and secure latching of the door by cooperation of the parts of the latching mechanism.

It is a further object of this invention to provide a latching and holding means for doors or similar closures of the type particularly adapted for use on hoppers of railway cars which in operation, assures that the closure is at all times, positively held in closing contact with the frame; is simple in construction; efficient in operation, and can be manufactured, installed and maintained with a minimum of expense and trouble.

A further object is to provide a latching means for doors of the above described type which is not subject to the liability of becoming accidentally disengaged in service, and which can be effectively manipulated by a simple operation to securely latch the door against the resistance of the weight of the load supported by the door in use.

A further object of this invention is to provide a closure for railway dump cars which is leak-proof and which will close more tightly than doors heretofore employed whereby to provide a car which may serve well for transporting powdered and finely divided materials, such as coal, sand, cement, and similar materials.

A further object is to provide a door which is capable of being constructed when desired, in a manner to provide a double surface sealing contact on all four edges thereof, when the door is in closed position, so that an improved seal is effected between the door and door frame. As an instant to this advantage, and as applied on doors for dump or hopper cars, the door or door frame may be provided with an overlapping flange so that each can be made as an integral piece and the other fitted tightly therein with a double lap at the joint.

A further object is to provide a door and door frame constructed as a complete unit which is capable of being made up independently of the hopper, car, or other device to which it is to be applied and thereafter mounted by mere attachment without relying upon parts of the hopper or car to constitute a part of its construction.

Although this invention is illustrated as applied to the hopper of a railway car, it is to be

understood that the invention is applicable to dump cars of other types and to all other hoppers and like devices, the construction of which will permit of its application thereto.

Various other objects not specifically enumerated are contemplated for this invention as will readily appear to one skilled in the art as the following description proceeds.

The disclosure of this specification will be more readily understood by referring to the accompanying drawings which illustrate preferred embodiments thereof as applied to railway hopper cars and in which:

Figure 1 is a side elevational view, partly in cross section, of the central portion of a railway hopper car equipped with doors and latching mechanism constructed in accordance with this invention, and

Figure 2 is an elevational view, partly in cross section taken on the line 2—2 of Figure 1, and looking in the direction of the arrows, and

Figures 3, 4 and 5 are enlarged side elevational views with Figures 3 and 4 in cross section, illustrating the latching mechanism, door and frame of this invention in various positions thereof, and;

Figure 6 is a view similar to Figure 2 illustrating a modification of this invention, and;

Figures 7, 8 and 9 are views similar to Figures 3, 4 and 5, respectively, illustrating various positions of a hopper door constructed in accordance with the modification of Figure 6.

By referring to the drawings it will be noted that the present invention is illustrated as applied to a hopper car of usual construction having side walls 10 and centrally disposed hoppers 11. The hoppers are located between the usual center sill 50 and side sill 51. As shown in Figure 1, each hopper comprises the usual slope sheets or shedding surfaces 12 and 13 respectively, and side walls 14. The closure or door of this invention is preferably mounted by means of a bracket 15 extending transversely across the under surface of the slope sheet 12, which bracket is preferably formed as an integral part of the door frame 21, hereinafter described. This part of the frame, namely the bracket 15 is attached to any part of the under structure of the car which will provide adequate support therefor, but preferably, as here shown, to the center sill as at 15' and the side sill as at 16'. Bracket 15 is provided with a plurality of extensions 16, having bearings 17 at their ends. A shaft 18 is rotatably mounted in said bearings and at points laterally of said bearings has fixedly or integrally attached thereto, a plurality of eccentrics 19, the outer surfaces of which form hinge bearing surfaces for the door 20.

The door is preferably cast as an integral piece

of metal but obviously may be of any suitable construction.

A metallic frame 21 is provided for cooperation with the door, attached by any suitable means such as rivets 22 to the lip or edge of the hopper opening. It is preferable likewise to form the frame as an integral casting but it may be fabricated from forged, bar or sheet stock without departing from the spirit of this invention. In 10 the form of the invention illustrated in Figures 2 to 5 inclusive, the frame is provided at each side and adjacent the bottom thereof with outwardly extending lugs 23, each having an inner inclined surface 24 adapted for latching cooperation 15 with lug 25 carried at the lower side corners of the door. The upper bracket 15 which supports the door hinge constitutes an upper part of the frame joining the tops of the side portions thereof.

20 Lugs 25 likewise are provided with inclined surfaces 26 for engagement with the surfaces 24 so that a bodily upward movement of the door will cause it to be moved in tight engagement with the frame.

25 At the upper edge of the door at spaced points in its width, hinge bearings 27 are provided for pivotal engagement on the outer cylindrical surfaces of the eccentrics 19. Frame 21 is preferably provided throughout its central location with 30 a reinforcing and strengthening rib 28 and a projecting lip or flange 29, the latter of which extends along the top, bottom and sides of the frame. The door 20 is also provided with a projecting flange 30 extending along the top, bottom 35 and sides thereof and so located as to enclose or lie outside of the projecting flange 29 of the frame.

40 It will be noted that the hinge bearings 27 are made as relatively large cylindrical loops having their inner diameters adjusted to provide good bearing fits on the eccentrics 19. With this construction, when the shaft 18 and the integrally formed or attached eccentrics 19 are held stationary, a fixed hinge is provided for the door by 45 means of the bearings 27 swinging on the external cylindrical surfaces of the eccentrics 19. However, when the shaft 18 is rotated to provide a corresponding movement of the eccentrics 19, the location of the axis of the door hinge on bearings 27 is bodily displaced so that a bodily movement is imparted to the door itself without, however, interfering with its pivotal movement on the bearing 27.

50 The flange 29 at the upper portion of the frame 21 is arranged on an incline which is so adjusted as to permit the upper flange 30 of the door, to move out of overlapping relationship therewith by the first movement of the eccentric 19. The rotation of the eccentric 19 first 55 causes the upper portion of the door to move to the right as shown in the figures of the drawings, and thence bodily downwardly whereby the upper lip is first removed from its overlapping position and freed for bodily movement with the 60 door.

65 It will thus be seen that the door 20 is capable of being moved manually or by any suitable mechanical closing device to a closed position with respect to the frame which movement 70 involves merely the swinging of the door on the bearing surfaces provided on the exterior of the eccentrics 19, and that after the door is in closed position that rotation of the shaft 18 (in a counter clockwise direction) will cause the door to be 75 bodily lifted to bring the lower edge thereof in

tight fitting engagement with the lower flange 29 of the frame, while at the same time, providing a relative movement between the inclined surfaces 24 and 26 of the lugs 23 and 25, respectively, to cause the door to wedge tightly, in 5 the direction of the closing swing, against the frame. As the customary construction for railway car hoppers involves an inclined outside surface as illustrated at the left hand edge of the hopper in Figure 2, it will readily appear that 10 a further advantage of this invention resides in the fact that the upward bodily movement of the door produces a tight wedging fit between the outside edges thereof.

15 The outer end of the shaft 18 has a hub 31 fixedly secured thereto which hub is provided with a tool or lever receiving socket 32. The hub 31 has a cylindrical portion 33 provided with a notch 34 at one point in its periphery disposed so as to be at the top thereof when the 20 door is in latched position as shown in Figure 5. Above the hub a slide guide bracket 35 is provided secured to the frame of the door or the car, and serving as a slide mounting for locking pin 36. The bracket 35 is preferably provided with a slot 37 in the outer surface thereof to slidably accommodate an extension 38 on the locking pin 36. This extension projects laterally toward the outside of the car in a position to be readily struck with a hammer or tool 30 by the car attendant so as to quickly and readily remove it from locking position in the notch of the hub.

25 In operation the attendant may disengage the locking pin in the manner above indicated and 35 thereafter by means of a lever or other tool, inserted in the socket 32 rotate the shaft 18 in a clockwise direction so as to cause the eccentrics 19 and door 20 to move downwardly to the position illustrated in Figure 4. Such movement of the door causes the lugs 25 to move clear and free of the lugs 23 whereupon the door is free to swing outwardly to the open position shown in full lines in Figure 4. Any suitable means may be utilized to cause the door to move 45 to open position but in installations of the type here illustrated, the door may be caused to move to the open discharging position by the weight of the door and the weight of the lading in the car.

30 In the modified form of this invention illustrated in Figures 6 to 9, inclusive, the parts, though generally similar, are modified to provide a latching of the door by bodily movement thereof downwardly instead of upwardly as in the form just described. In this form, the frame is constructed to provide a top, bottom, and side flange 40, which surrounds or encloses the edge of the door. At the bottom, the flange 40 is provided with one or more lug receiving openings 41 having inclined surfaces 43. The bottom edge 60 of the door is provided with one or more projecting lugs 42, disposed to extend into the openings 41 when the door is moved downwardly to latched position, and each lug 42 has an inclined surface for wedging cooperation with surfaces 43. Here the eccentrics are disposed with their high surfaces diametrically opposite to those of the first form whereby the eccentrics are in the lowermost position when the door is latched and are moved to the top position when the door is unlatched for free opening movement. It is believed that the operation of both modifications and their construction will be fully understood after inspection of the accompanying drawings, without further explanation, however 75

it may be mentioned that in the second modification, the door lies entirely within the frame when in closed position wherefore the same positive closing action is provided by the double lap seal as well as between the outside inclined side edges.

As it is well understood that the hopper constructions as represented in Figures 2 and 6 are provided in duplicate, one on each side of the center sill, it therefore will be appreciated that the operating shaft 18 may extend across the entire width of the car so as to control the doors on both sides by operation from either side. However, in most installations, it will prove more advantageous to have each door operated by a separate shaft.

The present invention provides a new and improved mounting for doors of the type here referred to together with novel, efficient, and improved latching means for the door. It is to be understood that any type of door closing mechanism may be employed. In many uses, a desirable and practical operation will result by relying on gravity supplied by the weight of the door and the lading in the car, for opening the door while utilizing manual force for lifting of the door for the closing movement.

It will be observed that the eccentrics employed for effecting the bodily movement of the doors are preferably designed to approach a dead center position when the door is latched whereby the parts will tend to remain in latching position without liability of accidental displacement. Although the locking pin positively maintains the parts in latch position, by virtue of the fact that the cams are on dead center when the door is latched, the locking pin is spared undue strain and wear in use.

When the door is to be unlatched, the rotation of the shaft and the eccentrics operates first to move the upper end of the door out of closing contact with the frame or slope seat and thereafter, by continued movement of the cam, to move the door bodily so as to free its lower end from locking engagement with the holding lugs at the bottom of the frame, whereupon the door is then free to swing to open position.

Because of the fact that the eccentrics approach a dead center position when moved to their final latched position, a relatively slight manual force applied for turning the shaft and eccentrics will develop a strong closing force on the door. Furthermore, the relatively great mechanical advantage produced by the eccentrics is increased by the wedging cooperation of the lugs at the bottom of the door and frame. A relatively slight movement of the door acts to develop a strong component of force in the closing direction. Accordingly, the parts can be made to fit tightly and snugly and yet be closed with great ease and furthermore small particles of lading or foreign material which may remain on the ledge of the frame will not prevent the doors from being properly closed against the strong and positive closing force developed by the eccentric and locking lug surfaces.

By providing a complete frame which also serves as a mounting for the door, the door and door frame assembly may be manufactured as a unit and applied to any suitable hopper or railway car. Furthermore, by virtue of the fact that the door fits either entirely within the frame or the frame fits entirely within the door as the case might be, a double lapped contact is effected for sealing the joint where the door and door frame meet. In both forms it will be noticed that the

top sealing lap affords no difficulty in operation because of the fact that the action of the eccentric causes the upper end of the door to move outwardly, whereby to free the overlapped flanges and thereafter to move the door bodily, either upwardly or downwardly, as the case may be, to disengage the latching lugs.

I claim:

1. A closure of the character described comprising a door frame and door, a hinge for said door at the top thereof, and cooperating locking lugs on the lower edges of said door and door frame, eccentric mountings for said door hinge adapted for rotation, said door and eccentric mountings being so constructed and arranged as to cause locking engagement of said lugs upon upward movement of said hinge and door.

2. A closure of the character described comprising a door frame and a door having a flange adapted to lie outside of said frame, a hinge for said door mounted for eccentric rotation so as to move said door upwardly and downwardly and lugs on said door and door frame adapted for locking cooperation upon upward movement of said door.

3. A hopper car of the character described comprising a hopper and a closure therefore, said closure comprising a door frame and a door, said door having a flange adapted to lie outside of said frame, a hinge for said door mounted for eccentric rotation so as to move said door upwardly and downwardly, and lugs on said door and door frame adapted for locking cooperation upon upward movement of said door.

4. A hopper car of the character described comprising a hopper and a closure therefore, said closure comprising a door frame and a door, said door having a flange adapted to lie outside of said frame, a hinge for said door mounted for eccentric rotation so as to move said door upwardly and downwardly, and lugs on said door and door frame adapted for locking cooperation upon upward movement of said door, and means for locking said eccentrically mounted hinge against rotation.

5. A closure of the character described comprising a door frame, and a door, a bodily movable hinge for said door for imparting bodily movement to said door, said door and frame having an inclined side edge, locking lugs on said door and frame whereby upon bodily movement of said door, said inclined edges approach and tightly engage each other and said lugs are engaged to hold said door in closed position.

6. A hopper car of the character described comprising a hopper and a closure therefore, said closure comprising in combination a door frame and a door, said door having a flange adapted to lie outside of said frame, a hinge for said door mounted for eccentric rotation so as to move said door upwardly and downwardly, and lugs on said door and door frame adapted for locking cooperation upon upward movement of said door, means for rotating said eccentrically mounted hinge and means for holding said hinge against accidental displacement.

7. A car door of the character described comprising a door and door frame, said door having an eccentric hinge connecting it to said door frame whereby said door is provided with a swinging opening and closing movement and a bodily movement upon displacement of its hinge axis, said door and door frame each having portions extending toward each other and adapted to overlap, said portions adjacent the hinge being dis-

posed at an angle and the remaining portions being disposed normal to the plane of the door opening, said hinge being adapted to permit said door to swing so as to cause said portions on the side opposite said hinge to overlap and assume a position approaching closed position and to thereafter move bodily to bring said overlapping portions in close sealing contact, and simultaneously with said last movement, to move said hinge side of said door bodily toward said door frame to thereby establish tight sealing contact between all of said portions of said door and door frame.

8. A car door of the character described comprising a door and door frame, said door having an eccentric hinge connecting it to said door frame whereby said door is provided with a swinging opening and closing movement and a bodily movement upon displacement of its hinge axis, said door and door frame each having portions extending toward each other and adapted to overlap, said portions adjacent the hinge being disposed at an angle and the remaining portions being disposed normal to the plane of the door opening, said hinge being adapted to permit said door to swing so as to cause said portions on the side opposite said hinge to overlap and assume a position approaching closed position and to thereafter move bodily to bring said overlapping portions in close sealing contact, and simultaneously with said last movement, to move the hinge side of said door bodily toward said door frame to thereby establish tight sealing contact between all of said portions of said door and door frame, said door and door frame having cooperating wedging faces adjacent the side thereof opposite said hinge which, during said bodily movement develop components of force causing movement of said door toward said door frame to thereby assist in the establishment of the sealing contact between all of said portions of said door and door frame.

9. A car of the character described having a hopper comprising downwardly extending hopper walls, a door frame attached to the edge of said hopper walls, said frame having angularly disposed portions adapted to form a double seal contact with corresponding portions of a door, a door and an eccentrically mounted hinge connecting said door and door frame, said door having angularly disposed portions adapted for sealing contact with the angularly disposed portions of said frame, the angularly disposed portions of said frame and door at the edges thereof adjacent the hinge being disposed at an angle greater than a right angle so that said door may be brought to closed position with respect to said door frame, without binding under the bodily displacement of said door produced by said eccentrically mounted hinge.

10. A car of the character described having a hopper comprising downwardly extending hopper walls, a door frame attached to the edge of said hopper walls, said frame having angularly disposed portions adapted to form a double seal contact with corresponding portions of a door, a door and an eccentrically mounted hinge connecting said door and door frame, said door having angularly disposed portions adapted for sealing contact with the angularly disposed portions of said frame, the angularly disposed portions of said frame and door at the edges thereof adjacent the hinge being disposed at an angle greater than a right angle so that said door may be brought to closed position with respect

to said door frame, without binding under the bodily displacement of said door produced by said eccentrically mounted hinge, said door and door frame also having cooperating wedging faces for exerting a closing component of force under the influence of the movement of said door caused by the eccentric mounting of said hinge.

11. A car door of the character described comprising a frame having inwardly disposed flanges comprising to abut the edge portions of the inside face of said door and other flanges disposed at an angle to said first-named flanges adapted to enclose the edge portions of said door, said door having an eccentrically mounted hinge for attaching it to said door frame, a wedge faced lug on said door frame adapted for cooperation with a corresponding lug on the swinging edge of said door, said angularly disposed flange on said door frame adjacent the hinge being disposed at an angle greater than 90 degrees with respect to its corresponding inwardly extending flange and said door having a correspondingly shaped edge adjacent the hinge for sealing contact therewith.

12. A car of the character described comprising a door and door frame, said door having edge flanges extending toward said frame and adapted to overlie and enclose said frame, an eccentrically mounted hinge for connecting said door and door frame, the flange on said door adjacent said hinge being disposed in a plane which is substantially parallel to the direction of movement of the hinge side of said door when said door is approaching the maximum closed position under the action of said eccentric hinge.

13. A door of the character described comprising a door and door frame, said door and door frame having cooperating surfaces to form a double seal, and an eccentrically mounted hinge for connecting said door and door frame, the cooperating surfaces of said door and door frame adjacent said hinge being disposed in a plane which is substantially parallel to the movement of said door when approaching the maximum closed position under the closing influence of said eccentrically mounted hinge.

14. A closure of the character described comprising a door frame and a door, said door frame and door having an inclined side edge and cooperating overlapping flanges, a hinge for said door and means for bodily displacing the axis of said hinge so as to give bodily movement to said door relative to said door frame in addition to its swinging movement on the axis of said hinge, said means serving to move said door bodily when in closed position in a direction to produce a closing and wedging action between the overlapping flanges of said inclined side edges.

15. A closure of the character described comprising a door frame and a door, each having an inclined side edge, cooperating overlapping flanges, and cooperating latching means with complementary wedging faces, a hinge for said door and means for bodily displacing the axis of said hinge so as to give bodily movement to said door relative to said frame, said means serving to move said door so that upon latching said door a wedging engagement is provided between said overlapping flanges of said inclined side edges and simultaneously therewith, between the complementary wedging faces of said latching means so as to impart a wedging force to said door, pressing said door in tight engagement with said door frame.

WILLIAM J. HOSCEIT.
